UNITED STATES PATENT OFFICE.

JOSEPH CUSENZA, OF DETROIT, MICHIGAN.

FURNACE ATTACHMENT.

Application filed February 9, 1928. Serial No. 252,965.

My invention relates to a new and useful improvement in a furnace attachment and while it is properly termed a furnace attachment it may be also constructed in the furnace as a permanent part thereof, as will appear from the description given.

An object of the present invention is to provide a most efficient furnace which is used for heating purposes, either in power plants or for heating dwellings, buildings and the like, and to provide a furnace in which a minimum amount of fuel will be consumed.

Another object of the invention is the provision of a device whereby a quantity of steam and air may be led into the furnace for combustion purposes and for assisting in the combustion of the fuel ordinarily burned therein.

Another object of the invention is the provision of a release valve adapted for setting the device into operation upon the developing of steam in the reservoir to a predetermined pressure.

Another object of the invention is the provision of a device of this class which will be simple in structure, economical of manufacture, durable and highly efficient in use.

Other objects will appear hereinafter.

The invention consists in the combination and arrangement of parts hereinafter described and claimed.

The invention will be best understood by a reference to the accompanying drawings which form a part of this specification and in which,

Fig. 1 is a side elevational view of the invention showing it installed in a furnace, which is shown in fragment.

Fig. 2 is a top plan view of the invention showing it installed in a furnace.

Fig. 3 is an enlarged fragmentary sectional view of a part of the device.

Fig. 4 is a central sectional view of a valve used in the invention.

In the drawings I have illustrated the device mounted on a furnace having a front wall 7, a side wall 8 and a grate 9 and provided with hot water pipes 10 which are normally positioned above the level 11 of the bed of coals. These pipes 10 are such as are commonly found in hot air, steam and hot water furnaces, and serve the purpose of supplying hot water to the hot water tank. They of themselves form no part of the invention, but are shown to illustrate the method of mounting the invention.

The pipe 12 which is connected to a suitable source of water supply, such as the city supply under pressure, is connected through the valve 13 and the pipes 14, 15, 16 and 17 to the pipe 18 which extends inwardly of the furnace and is connected in communication with the large pipe 19, this pipe 19 being connected by the return 20 to the pipe 21 which connects through the return 22 to the pipe 23, the return 24 to the reservoir 25. An outlet pipe 26 connected to this reservoir, passes through the pressure pop valve 27, this valve being regulated to open upon the building of a predetermined pressure in the reservoir 25. A T 28 is in communication with the pop valve 27 and also with the pipe 29 which communicates with the pipe 30 projected inwardly of the furnace below the grate 9 and provided at its end with a nozzle 31 having a flattened end 32. Connecting with the T 28 is a small pipe 33 which is threaded into the head 34 which is mounted in the pipe 35. A pocket 36 is formed in the head 34, leading outwardly from which and extending axially of the pipe 35 is a tube 37. A screw 38 is threaded in the head 34 and serves as a needle valve operating in the end of the tube 37. This pipe 35 is projected inwardly of the furnace, suitable nuts 39 and 40 being adapted to clamp the front wall 7. The pipe 35 is projected inwardly of the furnace above the normal level 11 of the coal bed. The inner end 41 of the pipe 35 is reduced and spot welded as at 42 to a cup-shaped member 43 which is provided with a plurality of perforations 44. Leading outwardly from the T 45 into which the pipes 17 and 18 lead, is a pipe 46 provided with a stop cock 47. Plates 48 and 49 cooperating with suitable bolts 50 are used to secure the pipe 19 upon the hot water pipes 10, the pipe 19 being offset as at 50' to bring the major portion of the length of the pipe 19 to lie between the pipes 10.

The valve 13 is provided with a plug 51 having a valve seat therein in which engages the end of the screw or needle valve 52 which threads into the block 53 screwed into the shell of the valve 13, thus affording a means for regulating the amount of water which may flow from the source of supply through the pipe 12 into the pipe 19.

In operation, after the bed of coals has been placed on the grate 9 and ignited, the valve 47 is opened to permit the escape of such surplus water as may have collected in the heating

coils consisting of the pipe 19, the returns 20, 21 and 24, and the pipes 21 and 23, as well as the reservoir 25. The valve 47 is then closed and the needle valve 52 opened sufficiently to permit the water to flow into the pipe 14 in small quantities, preferably drop by drop. As this water is delivered to the heating coils, it is turned into steam which, in passing through the heating coils, is superheated. 10 When a pressure has been built up in these coils and in the reservoir 25 and the pipes 26 sufficiently to open the valve 27, this superheated steam will pass through the pipes 29 and 30 outwardly from the flattened end 32 of the nozzle 31 and thence upwardly through the burning coals on the grate. At the same time, a small quantity of the steam will pass through the pipe 33 into the pocket 36 through the tube 37 and outwardly through 15 the perforations 44. As this steam travelling through the tube 37 which is positioned axially of the pipe 35 sets up a vacuum, air will be drawn in through the opening 54, so that the steam and air will commingle in the pipe 35. The pipe 35 is not spot welded to the cup-shaped member 43 around its entire periphery, but at separated points, preferably three or four in number. Consequently, the 20 heated gas from the interior of the furnace will also be drawn into the cup-shaped member 43, and this heated gas, together with the air and the small quantity of steam which passes through the tube 37 will be expelled through the perforations 44. This steam and 25 air will assist combustion of the gases which rise from the bed of coals, and the superheated steam expelled from the nozzle when brought into contact with the burning coals will be broken up into its constituent gases 30 and burned. This operation will continue so long as the pressure in the coils and reservoir 25 and the pipe 26 is sufficient to maintain the valve 27 in open condition. It is desirable that this valve 27 be set to open at 35 a pressure slightly less than the pressure of the water supply in the pipe 12. In many cities this water supply pressure is but twenty-five pounds, and in such case it would be preferable to have the valve 27 set to open upon a building up of a pressure of approximately twenty pounds, so that a backing up 40 of the water into the water supply pipes could not take place.

With a device constructed in this manner 45 a considerable saving of fuel is effected as the gases provided by the steam which is delivered into the bed of coals forms a considerable part of the heating function desired. Under normal conditions the device will continue to operate and eject from the nozzle 31 the superheated steam so long as the bed of coals on the grate 9 are of combustible quality, that is, until the bed of coals has been 50 burned, in which event the valve 27, upon the lowering of the pressure below the pre-

determined amount, will close and the device cease to operate until the heat from the coals on the grate 9 have again raised the superheated steam to the predetermined pressure.

The device constructed in this manner is 70 one which is very easily and quickly installed on a furnace already built, and very easily built into a furnace in the course of its manufacture. The durability and simplicity of the device is believed evident from the description, and experience has proven, after repeated tests, the efficiency of the structure and the economy resulting from its operation. 75

After operation has ceased and prior to generating steam in the reservoir and heating coils there is built up a pressure of over the required amount to open the valve, the water which is in the reservoir and heating coils and which will be forced from the nozzle will be deposited in the ash pit below the grates and 85 the live coals in no serious manner affected.

While I have illustrated and described the preferred form of my invention, I do not wish to limit myself to the precise details of structure shown, but desire to avail myself of such variations and modifications as come within the scope of the appended claims. 90

Having thus described my invention what I claim as new and desire to secure by Letters Patent is:

1. A device of the class described adapted for use on a furnace having a combustion chamber and grates positioned below said combustion chamber, comprising: heating coils extended into said combustion chamber; means for delivering water to said heating coils; a nozzle positioned below said grate; and a valve automatically establishing communication between said nozzle and said heating coils upon building up of predetermined pressure in said heating coils. 100

2. A device of the class described adapted for use with a furnace having a combustion chamber and grates positioned therebelow, comprising: heating coils in said combustion chamber; means for delivering liquid to said heating coils; a nozzle positioned to discharge below said grate; means for connecting said nozzle to said heating coil; a valve interposed between said nozzle and said heating coil for controlling said communication, said valve being automatically opened upon building up of a predetermined pressure in said heating coils. 110

3. A device of the class described adapted for use with a furnace having a combustion chamber and grates positioned therebelow, comprising: heating coils in said combustion chamber; a reservoir in said combustion chamber in communication with said heating coils; means for delivering liquid to said heating coils; a conduit communicating with said reservoir; a nozzle communicating with said conduit and adapted for discharging into said furnace below the coals on said grate; 120

125

130

and a valve interposed between said conduit and said nozzle and automatically operable for establishing communication between said nozzle and said conduit, upon building up of a predetermined pressure in said reservoir.

4. A device of the class described adapted for use with a furnace having a combustion chamber and grates positioned therebelow, comprising: heating coils in said combustion chamber; a reservoir in said combustion chamber in communication with said heating coils; means for delivering liquid to said heating coils; a conduit communicating with said reservoir; a nozzle communicating with said conduit and adapted for discharging into said furnace below the coals on said grate; a valve interposed between said conduit and said nozzle and automatically operable for establishing communication between said nozzle and said conduit, upon building up of a predetermined pressure in said reservoir; a pipe projecting inwardly of said combustion chamber and communicating at its outer end with the atmosphere; and means operable upon the opening of said valve for effecting an induced draft inwardly of said pipe.

5. A device of the class described adapted for use with a furnace having a combustion chamber and a grate positioned therebelow, comprising: heating coils positioned in said combustion chamber; a nozzle communicating with said heating coils and adapted to discharge below the coals on said grate into said furnace; means for delivering liquid to said heating coils; a valve positioned between said nozzle and said heating coils and automatically establishing communication therebetween upon building up of a predetermined pressure in said heating coils; means projecting into said combustion chamber and communicating with the atmosphere; and means for setting up an induced draft through said last named communicating means upon the opening of said valve.

6. A device of the class described adapted for use with a furnace having a combustion chamber and grates positioned therebelow,

comprising: heating coils in said combustion chamber; means for delivering liquid to said heating coils; a reservoir in communication with said heating coils; a conduit communicating with said reservoir and extending exteriorly of said furnace; a nozzle communicating with said conduit and adapted to discharge into said furnace below the coals positioned on said grate; a valve interposed in said conduit for controlling communication between said nozzle and said reservoir, and automatically operable to establish said communication, upon building up of a predetermined pressure in said reservoir; a pipe projecting inwardly of said combustion chamber and communicating at its outer end with the atmosphere; and means operable upon the opening of said valve for effecting an induced draft inwardly of said pipe.

7. A device of the class described adapted for use with a furnace having a combustion chamber and grates positioned therebelow, comprising: heating coils in said combustion chamber; means for delivering liquid to said heating coils; a reservoir in communication with said heating coils; a conduit communicating with said reservoir and extending exteriorly of said furnace; a nozzle communicating with said conduit and adapted to discharge into said furnace below the coals positioned on said grate; a valve interposed in said conduit for controlling communication between said nozzle and said reservoir and automatically operable to establish said communication, upon building up of a predetermined pressure in said reservoir; a pipe projecting inwardly of said combustion chamber and communicating at its outer end with the atmosphere; a tubular member extending axially of said pipe; a by pass connecting said tubular member with said conduit, said tubular member conducting steam under pressure upon opening of said valve into said pipe for effecting an induced, inwardly directed draft; and a perforated cup-shaped member embracing the inner end of said pipe.

In testimony whereof I have signed the foregoing specification.

JOSEPH CUSENZA.
